DISPLAY CARTON

Raymond A. Cote, Doraville, Ga., assignor to Riegel
Paper Corporation, New York, N.Y., a corporation of Delaware

Filed Mar. 16, 1966, Ser. No. 1,478

Term of patent 14 years

(Cl. D58—12.6)

FIG. 10

FIG. 11

FIG. 12

FIG. 1 is a perspective view of a display carton showing my new design;

FIG. 2 is a front elevational view thereof;

FIG. 3 is a side elevational view thereof;

FIG. 4 is a rear elevational view thereof;

FIG. 5 is a top plan view thereof;

FIG. 6 is a bottom plan view thereof;

FIG. 7 is a perspective view of a modified form of the display carton of FIG. 1 wherein the top is convex;

FIG. 8 is a front elevational view thereof;

FIG. 9 is a side elevational view thereof;

FIG. 10 is a rear elevational view thereof;

FIG. 11 is a top plan view thereof; and

FIG. 12 is a bottom plan view thereof.

The broken line showing of the light bulb is for illustrative purposes only. The essential features of my design reside in the generally shallow V-shaped window configuration in the carton side walls and the arcuate configurations of the upper and lower portions of the carton substantially as described and shown in the drawings.

I claim:

The ornamental design for a display carton, substantially as shown and described.
